ADDRESSING MACHINE

Harmon P. Elliott, Watertown, Mass.

Application June 7, 1939, Serial No. 277,770

26 Claims. (Cl. 101—48)

The present invention relates to addressing machines of the type wherein the data to be printed is carried by movable printing devices and, as illustrated herein, relates more particularly to machines of the type wherein successive address printing stencils are fed into printing position and in which the number of impressions made by any one of the printing devices is automatically controlled.

In the use of an addressing machine, in an insurance office, for instance, each of the stencils may contain the name and address of the policy holder, the policy number, the premium due date and other accounting data. It is or can be common practice to send out an expiration notice and a premium receipt to a policy holder. The notice and the receipt are usually printed on one sheet of paper and the two parts are usually separated by the policy holder who retains the expiration notice and returns the premium receipt to the insurance company with his remittance. These forms are printed on sheets of paper which are of sufficient size to contain a plurality of successive expiration notices and premium receipts of different policy holders to be printed thereon.

The expiration notice and the premium receipt are printed successively on a single sheet which may contain three or more sets of notices and receipts. This is done to facilitate and speed up the addressing operation since three sets of addresses may be printed with only one handling of the paper sheet. This method of handling or printing expiration notices and premium receipts necessitates the severing of pairs of notices and receipts from the sheet. While this severing operation may be performed in a separate machine or manually, such a method increases materially the cost of preparing such notices and receipts.

One object of the present invention is to provide means for automatically severing sets of forms after the addresses have been applied to a continuous sheet containing the sets of forms. As illustrated, the present machine is provided with a printing head and means for moving the sheet to be addressed step by step past the printing mechanism to a feed roll which is operative to continue the feed of the sheet after the last address printing operation is performed thereon and as another sheet is placed in position between the step by step feeding means. The first mentioned sheet is then fed laterally to a severing mechanism which severs the sheet into sets

of forms containing the expiration notice and a premium receipt.

Another object of the invention is to provide improved means for delivering sheets after they have been addressed to a laterally movable feeding device.

Still another object of the invention is to provide means for feeding the addressed sheets laterally to the severing mechanism.

The illustrated machine is provided with means for applying a plurality of sets of different addresses to a sheet as it is moved step by step through the printing station between successive address applying operations. After the last address has been applied to the addressed sheet, a pair of cooperating feed rolls are conditioned to feed the addressed sheet to a position where the sheet is engaged by a lateral sheet pusher to move the sheet laterally. The machine is provided with a plurality of severing devices for severing the sheet into a plurality of sets of forms, each set containing the same address and different sets each containing different addresses. The lateral sheet pusher feeds the addressed sheet laterally to the action of the severing means and feeding devices associated with the severing means deliver the severed sets of forms to an endless belt conveyor which is so arranged that the severed sets of forms are delivered to a receiver from which the sets are removed periodically. The machine is also provided with means for receiving the severed feed tab of the sheet, the conveyer being so located with respect to the severing means which separates the feed tab from its associated form that the tab is free to fall into a chute or guideway from whence it is delivered to the feed tab receiving means.

Another object of the invention, accordingly, is to provide an improved addressing machine in which the above mentioned features are embodied.

Another object of the invention is to improve generally upon the construction and operation of printing and addressing machines.

With the above and other objects and features in view the invention will now be described with particular reference to the accompanying drawings which illustrate a preferred embodiment of the invention and in which:

Fig. 18 is a diagrammatic plan view showing the relation of the parts of the machine after the sheet has been fed to the lateral feeding mechanism;

Fig. 19 is a similar view showing the position of the sheet after it has passed through the severing mechanism;

Fig. 20 is a view on an enlarged scale of a sheet containing a plurality of expiration notices and premium receipts; and

Fig. 21 is a plan view of a stencil particularly adapted for use with the illustrated machine.

The illustrated machine is arranged to operate upon printed sheets having a plurality of sets of printed forms each set comprising forms of different character but relating to a single transaction or to a series of transactions with one person to whom the forms are addressed.

As illustrated in Fig. 20, a sheet 30 contains three sets of printed forms. Each set comprises an expiration notice 32 and a premium receipt 34. Both the notice and the receipt are provided with blank portions 36 and 38, respectively, which are to receive the name and address of the policy holder to whom the notice and receipt are to be sent. Blanks or spaces 40, 42 are provided below the space or blank 36 on the expiration notice in which the policy number and the premium due date are to be printed. The premium receipt 34 contains similar spaces 44 and 46, one of which receives the policy number and the other receives the date at which the insurance covered by the premium to be paid expires. It is apparent that

other blanks or spaces may be provided, if desired, to receive additional data.

The address and other data, above referred to, as illustrated are printed on the blanks by the use of stencils 48. These stencils are well known in the art and comprise a pair of thick outer or facing paper sheets and a middle or welt sheet. The outer or facing paper sheets are provided with aligned rectangular openings 50. The welt sheet extends into the space between the aligned windows and is provided with an opening and a stencil sheet 52 overlies the opening in the welt sheet and is located within the windows of the facing paper sheet. The stencil sheet 52 is adhesively secured to the edges of the welt sheet adjacent to the opening therein. The stencil sheet 52 is adapted to receive the address and other data to be printed. The stencils 48 are also provided with control perforations 53, or equivalent means, suitably positioned in the stencil to permit the selection for printing of certain stencils only of a collection.

The machine embodying the present invention comprises a frame including a table or bed 54 supported on legs 56, 58. A pair of rails 60 are spaced above the top of the table and extend in spaced horizontal parallel relation across the table and constitute a track in which the successive stencils 48 are advanced from a vertical stack of stencils contained in a stencil holder 62 located above the left hand end of the track and through a printing position and into a stencil receiver 64 located at the other side of the machine and below the spaced rails 60.

The printing mechanism includes a substantially vertically movable printing head 66 located above the stencil track and a vertically movable anvil 68 located below the stencil track. The impression or printing head 66 is carried by the forwardly extending ends of arms 70 which are carried by a horizontal loop frame 72 disposed at the rear of the stencil track and pivoted to a shaft 74 (Fig. 2) carried by a bracket 76 secured to the under side of the table 54. The impression head is supplied with ink by means of a horizontally swinging ink roller 78 carried by a pair of swinging arms 80 which are pivotally mounted in the forwardly extending ends of arms 82 secured to the top of a bracket 84 which in turn is secured to the bed 54 of the machine rearwardly of the loop frame 72. The ink roll 78 is supplied with ink from any suitable ink distributing mechanism and the roll 78 is moved across the bottom face of the impression pad 66 in a manner not necessary to describe in detail herein.

The anvil or platen 68 is mounted between and forms a part of the forward ends of arms 86 which are pivoted at 88 to the rear part of the bracket 76. The platen and the printing head are adapted to be reciprocated toward and away from each other in timed relation so that the platen supports a work sheet beneath and in contact with the stencil 48 at the time that the printing head 66 moves into engagement with the stencil 48.

The operating mechanism for reciprocating the printing head and the anvil includes a horizontal shaft 90 supported by the bracket 76 providing pivotal support for an operating arm 92 which is reciprocated in a vertical direction. The arm 92 is pivotally connected through a link 94 with the lower end of an arm 96 depending from the loop frame 72. It is evident that the reciprocation of the arm 80 effects the reciprocation of

the printing head 62. The reciprocation of the arm 92 also effects the reciprocation of the generally vertically extending cam arm 98 which cooperates with a cam roller 102 carried by the platen for effecting the reciprocatory movement of the anvil or platen 68.

The operating arm 92 (see Figs. 2 and 4) is provided at its free end with a latch 104 which is pivoted thereto and which is normally urged toward an operating sector 106 to bring a latch projection 108 into engagement with a notch 110 formed in the sector 106. The operating sector 106 is pivoted on the shaft 90 so that the arm 92 and the sector 106 normally reciprocate in unison. The engagement of the latch 104 with the sector 106 is under control of the selector mechanism and is arranged at times to be disengaged from the sector as will later be explained. The sector 106 is reciprocated by means of a connecting rod 112 (Fig. 2) from a power plant 114.

The power plant 114 as is usual in machines of this type, has a jack shaft 116 driven from the motor 117, which shaft is arranged to be constantly rotated during operation of the machine. The shaft 116 drives a shaft 118 through gear connections not shown. The driving connection between the shaft 116 and the shaft 118 includes a one revolution clutch of well-known construction which is under the control of a foot pedal 120 which effects one complete reciprocatory movement of the connecting rod 112 and hence one complete cycle of operation of the machine for each depression and release of the pedal 120. When, however, the pedal is held down by the operative in the normal operation of the machine, the machine will operate continuously. The treadle or foot pedal 120 is connected by a link 122 to a hand lever 124 located at the right hand side of the table, see Fig. 1, so that the control of operation of the machine may be effected by hand if desired, the machine ordinarily performing several cycles before it need be stopped for a new work sheet.

As is common practice in addressing articles, it is desired to address forms by selected stencils only contained within the stencil holder 62. To this end, selector mechanism is employed to condition the printing mechanism to operate only upon desired or selected stencils and to permit the passage of undesired stencils through the printing position without printing therefrom. If a selected stencil is in printing position and the next stencil to be sensed by the selector happens to be one that is not desired to be printed, the selector mechanism, as commonly arranged, operates to disable the printing mechanism following the first printing operation on the stencil that is in printing position and would effect the feeding movement of such stencil out of printing position. With the present construction, however, only one of the desired two impressions from the same stencil would be made. Therefore, the selector mechanism is so arranged as to sense a stencil only during alternate cycles of operation of the printing mechanism, providing a wanted stencil is in printing position between the platen and impression pad. If, however, an unwanted stencil is in printing position the arrangement of the mechanism is such that the selector will feel, or make a sensing operation on, successive stencils during each cycle of operation of the machine, the printing mechanism being disabled, until a stencil that is wanted for printing is positioned in the printing position. The arrange-

ment of the mechanism is such, as will presently appear, that a fresh stencil is advanced at each cycle of operation of the machine so long as there are unwanted stencils in printing position, thereby

5 to move an unwanted stencil into and out of printing position in one cycle of operation, but when a wanted stencil is in printing position the arrangement is such that a fresh stencil is advanced during every other cycle of operation of the machine, thereby permitting two printing operations to be made on the same wanted stencil.

In Figs. 1, 5, 6, 7, and 9, there is shown a selector mechanism which includes the selector 125 mounted in a frame 126 which is movable angularly toward and away from a stencil spaced two stations away from the printing position. The selector frame 126 is movable angularly in a direction transversely of the stencil guideway to permit sliding contact between the ends of selector pins 128 mounted in the bracket 125 and a stationary contact plate 130 to insure that a good electrical connection is made between the pins 128 which are adapted to enter underlying selector perforations in the stencil and the contacts 130 cooperating therewith. In the specific disposition herein illustrated, the arrangement is such that if a pin 128 enters a selector perforation during descending movement of the selector frame 126, an electric circuit thereby is completed which conditions the printing mechanism for a printing operation. The angularly positioned selector guide 132 is secured to the forward rail 60. The selector frame 126 is guided for movement in this guideway 132 and, as is now well-known in the art, is provided with teeth which are arranged to mesh with a gear sector fixed to a horizontal shaft 134 which is journaled in the guide member 132. An arm 136 is fixed to one end of said shaft 134 and is pivotally connected to a substantially horizontal link 138. The oscillations of the shaft 134 are effected through the arm 136 and the link 138 by connections to one end of a horizontally extending shaft 140 located at the rear part of the table and journaled in suitable bearings 142 secured to the bed 54 of the machine. The shaft 140 has fixed to its other end an arm 143 which extends below the table 54. The lower end of the depending arm 143 is provided with a cam roller 144 which engages the cam face of a cam plate 147 fixed to the operating sector 106. The arrangement is such that upon the latter portion of the upward movement of the sector 106 the roller 144 passes along the lower inclined face 148 of the cam and hence the lever and the shaft 140 are permitted to be moved in a clockwise direction, as viewed in Fig. 4, by the tension of a spring 150 connected to the arm 142. This movement of the shaft 140 takes place during the latter part of the printing operation and effects the downward movement of the selector frame into stencil sensing position.

The purpose of the completion of the electric circuit through or under the control of the stencils is to effect the energization of an electromagnet 154 (Fig. 3) which is located at the rear of the machine. This magnet controls the operation of the printing mechanism. Since, however, the selector is located two stencil positions away from the printing position the completion of the circuit through the stencil cannot be utilized immediately to effect the energization of the electromagnet, as improper control of the printing mechanism would be effected. Hence the control of the electromagnet 154 by the selector is effected through a delay, or accumulator, mecha-

nism, shortly to be described, so that the desired control of the printing mechanism is effected. For a clear understanding of the need for and the action of the accumulator mechanism, the control of the printing mechanism by the electromagnet 154 will be described first.

The electromagnet 154 when energized operates to pull down one end of the lever 160 which is pivoted between its ends and raises the other end of the lever 160 to lift a latch 158 which is loosely mounted on the aforesaid shaft 140. The latch 158 controls a trifurcated lever 160 which is pivoted intermediate its ends at 162 to a depending bracket 164 fixed to the rear of the machine bed 54. A lower furcation of the lever 160 is provided with a cam surface 166 which is arranged to engage a cam roller 168 rotatably carried by the upper end of the latch 104. It is apparent that the lever 160 controls the connection between the operating arm 92 and the sector 106. A spring 170 is connected to the lever 160 and to the frame of the machine in such a manner as normally to urge the lower end of the lever away from the cam roll 168. The upper furcation of the lever 160 is provided with a pair of vertically spaced upper and lower detents 160a, 160b and the latch member 158 is provided with a detachably reversible hook member 172 which is arranged between and adapted, in the position illustrated in Fig. 4, to engage the lower detent 160b. Thus, with the arrangement shown, which is the normal position of the parts, the lower end of the lever 160 is held in engagement with the latch 104 so that the printing mechanism is normally disabled. When however, the electromagnet 154 is energized to disconnect the latch 158 from the lever 160 thereby releasing the latch 104 and connecting the operating arm 92 and the sector 106 to effect a printing operation. The lever 160 is restored into engagement with the latch 158 during a part of every printing operation by means of a cam block 174 carried by the operating sector 106 and engaging a cam roll 176 on the lever 160 which rotates the lever 106 in counterclockwise direction to reset the latch. With the mechanism so far described, the lever 160 is reset after every printing operation to disconnect the operating mechanism from the operating sector 106.

With this method of operation, only one impression is made from the same stencil. It is necessary, therefore, to modify the above manner of operation in such a way that the operating arm 92 and the sector 106 will remain engaged for two complete printing operations. Duplicate printing mechanism is provided by which this result may be obtained and includes an arm 178 fixed to the end of the operating arm 92 by a stud bolt 180 which is fixed to the end of the arm 92 and on which the latch 104 is pivoted. Said arm 178 at its free end is provided with a screw 179 that is loosely located in a longitudinally elongated slot 181 of a generally vertical link 182. The upper end of said link is pivotally connected to the free end of a pawl carrying lever 183 pivoted on a shoulder screw 185 carried by the frame of the machine. Said lever carries a pawl 184 which cooperates with the teeth of a ratchet wheel 186 loosely journalled on said shoulder screw. A cam disc 192 and a retaining drum together with the ratchet wheel 186 are pinned or otherwise suitably joined together for conjoint rotation about the shaft 188. The cam disc 192 is disposed beside and under the latch 158 and the latch has a depending projecting 194 that rides upon the cam disc 192. The cam disc 192

has a plurality of lobes which successively engage and raise the latch 158. The arrangement is such that when a lobe is under the latch projection 194 the latch is supported in an elevated position and is disengaged from the tripping lever 160 for the latch 104. When the projection 194 is located in the valley between the lobes, the latch 158 is free to move downwardly and thereby engages and locks the tripping lever 160 in such position that it holds the latch 104 disengaged from the operating sector 106. The cam disc is advanced intermittently by the strokes of the operating arm 92 in a step by step manner, each step being equal to one half of the distance between two consecutive lobes so that a lobe and a valley are positioned successively under the projection 194. It is evident that with this construction the latch 172 is held in an elevated position during every alternate printing cycle so that it cannot engage and lock the tripping lever 160 and thus hold the latch 104 out of engagement with the operating sector 106. It is apparent that two printing operations are effected on only one stencil for one feeling or sensing operation thereof.

As hereinbefore stated, the selector or sensing operation for conditioning the printing mechanism is located two stations in advance of the printing station. As has been set forth hereinbefore, it is necessary to provide means for delaying the operation of the selector mechanism until the selected stencil arrives in printing position. To this end, the present machine is provided with a delay or accumulating mechanism (Figs. 5, 6, and 7) 198 which is located below the table 54 and is supported in a bracket 200 suitably secured to a bracket or shelf 202 fixed to one of the upright supporting members 52. The upper end of the bracket 200 has journalled therein a shaft 204 to one end of which is fixed a ratchet wheel 206 and to the other end of which is fixed an accumulator wheel 208. The ratchet wheel 206 is reciprocated during each cycle of the machine through a link 210 having at one end a lost-motion connection with an arm 212 fixed to the shaft 90 to which the operating arm 92 is also fixed. The other end of said arm or link 210 is pivotally connected to a pawl carrying arm 211 journalled on the aforesaid shaft 204 and carrying pawl 213 engageable with the teeth of the ratchet wheel so that the ratchet wheel and hence the accumulator disc is caused to advance angularly by intermittent steps equal to the angular spacing between the teeth of the ratchet wheel. The accumulating disc 208 is provided with a plurality of headed pins 214 corresponding in number and spacing to the number and spacing of the ratchet teeth, which pins are arranged for limited sliding movement axially of the accumulating disc 208.

Thus when the selector mechanism is operating upon a selected stencil and the electric circuit is completed between one or more pins 218 and the stationary contact 130, an electromagnet 216 is energized, see circuit diagram, Fig. 14, and operates to move an arm 218 in a clockwise direction as viewed in Fig. 6 and against one of the pins 214 to move the pin to the right. In this displaced position, the head 219 of the pin, due to the advance of the accumulator disc 208, will engage a switch operating arm 220 which thereupon will be moved in a counter-clockwise direction as viewed in Fig. 7 to close an electric switch 222. When the switch 222 is closed, the electrical circuit for the first mentioned magnet

154 is completed to condition the printing mechanism for a printing operation as has been explained. It is to be noted that the arm 220 is so located that the displaced pin 214 does not strike the arm 220 until some time during the second step of advance of the accumulating disc following the initial displacement of the pins. The accumulating mechanism thus permits the action of the magnet 154 to be delayed until the selected printing device or stencil 48 is moved into printing position. The displaced pins are returned to their normal position by a cam plate 199 fixed to the accumulator support which is arranged to engage the displaced pins after they have passed the switch operating lever 220. The displaced pins are returned to normal position before the displaced pins have rotated sufficiently again to be in position to be engaged by the magnet lever 216.

Since two printing operations are made upon the same stencil selected for printing, it is necessary that the selector frame be disabled during every alternate printing operation and also that the stencil advancing mechanism be disabled during alternate printing operations. If, however, the sensed stencil under the selector frame is found to be one that is not required for printing, then the selector mechanism and also the stencil advancing mechanism are arranged to make an operation for each cycle of operation of the machine until a sensed stencil is found to be one from which printing is desired and has been moved into printing position. Referring now particularly to Figs. 1, 8, and 8a it is to be noted that stencil advancing mechanism includes a pusher 224 which advances the successive lowermost stencils from the stack into and along the stencil track. The pusher 224 is reciprocated by a connecting rod 226 which is located under the table 54 and is pivotally connected to the forwardly extending arm 228 of a bell crank lever having a vertical hub 230 pivoted to the table and having an angularly related arm 232, the end of which operates in a cam slot 234 formed in the operating sector 106. The cam slot 234 is so shaped as to effect a complete reciprocation of the pusher for each complete reciprocation of the sector 106. The connection between the pusher and the connecting rod 226 is by means of a pin 236 connected to the pusher and operating in a longitudinal slot 238 formed in the connecting rod 226. The slot 238 has at one end a lateral extension 240. When the pin 236 is in the extension 240 the pusher and the connecting rod 226 are operatively connected. When, however, the link 228 is moved to the position shown in Fig. 8, so as to position the pin 236 in line with the slot 238, the connecting rod is free for reciprocation without transmitting that reciprocation to the pusher.

The control of the connection between the connecting rod 228 and the pusher 224 is effected through cam mechanism which is generally similar to the cam mechanism for controlling the operation of the printing mechanism controlling lever 160. The cam mechanism includes a movable lobe 242, a brake disc 244, and a ratchet disc 246 which are pinned or otherwise secured together. The parts mentioned just above are fixed to a vertical shaft 248 journaled in a bracket 250 carried by the table 54 close to the connecting rod 226. A swinging arm 252 is located between the cam and the connecting rod 228. The arm 252 is pivotally mounted at one end to the bracket 250 and at its other end carries rolls 254, 75

255 one of which is arranged to engage the movable lobe cam and the other is arranged to bear against the connecting link or arm 228. A spring 256 is connected at one end to the link 228 and at its other end to the bottom of the table 54 in such a manner that the link 226 is held against the rollers 255. It is evident therefore, that when the cam 242 is rotated, the arm 228 will alternately be swung so that in one position the pin 236 fits into the lateral extension of the slot 240 to permit feeding of the stencils and in the other position the pin 236 will be located in alignment with the slot 238 so that the feeding movement of the pusher will not be effected.

15 The rotation of the cam disc 242 is effected by the operating sector 106 but only as determined by the selector mechanism. The cam disc 242 is adapted to be advanced progressively in an intermittent manner by means including an arm 258 which carries a ratchet engaging pawl 260. The arm 258 is rotatably mounted on the shaft 248 and at its other end carries a pin 262 which is in a longitudinal slot 264 formed in the free end of a link 266 pivoted at its other end to the arm 229 of bell crank lever 228. The slot 264 is provided with a lateral extension 268. Thus, when the pin 262 is in the lateral extension the movement of the arm 266 is transmitted to the arm 258 thus advancing the cam step by step, but if the pin 262 is located in alignment with the slot 264, the arm 266 is free to move without transmitting reciprocating movement to the pawl carrying arm 258. The arm or link 266 is normally urged in a direction toward the cam member 242 through a spring 268 connected at one end to the arm 266 and at its other end to the bracket 250. The arm 266 is engaged by a pin 269 carried by one end of a bar 270 which in turn is pivotally connected to an arm 272 which is fixed to the pivot 162 to which the lever 160 is fixed. Thus, when the lever 160 is released from the latch 172 the link 266 is moved into the position shown in Fig. 8 with the pin 262 in the lateral extension 268. When, however, the lever 160 is in the position shown in Fig. 4, the arm or link 266 is free to move under the influence of the spring 269 to position the pin 262 in the end of the long slot 264. It is apparent therefore, that with this construction the cam 242 will be rotated intermittently only when the lever 160 is free from the latch 172. In other words, the cam disc 242 will not be rotated step by step unless the operating arm 92 and the operating sector 106 are connected and thereby operating the impression head 66 and the platen 68. In the idle position of the cam 242, as thus described, a dwell or valley of the cam confronts the roller 254 so that the pusher is thus conditioned to advance successive stencils on successive cycles of the machine.

60 The stencil feed controlling mechanism also controls the reciprocation of the selector. To this end a control cam disc 233, see Fig. 1, is located above the table and is fixed to and driven concurrently with the aforesaid cam 242. Said cam 233 is provided with a series of arcuate notches 235 and alternate circumferential dwell portions 237 corresponding in spacing with the lobes and dwell portions of the cam 242. A rod 239 is provided with a roller 241 which is adapted to enter any one of said notches and is reciprocable in the radial direction of the cam and pivotally connected to a depending arm 243 fixed to the aforesaid selector operating shaft 140. The arrangement is such that if a circumferential lobe 237 of the cam confronts the roller 241 it pre-

vents the shaft 140 from being turned in a direction to permit the lowering of the selector frame into sensing relation with an underlying stencil. Since the cam 233 advances concurrently with the aforesaid stencil feed controlling cam 242 it is apparent that the selector can be reciprocated into and out of sensing relation with the stencils both once for every cycle of operation of the machine or once for every two cycles of operation of the machine. In both instances, however, the selector mechanism makes but one sensing operation on any underlying stencil.

Referring now to Fig. 1 it will be noted that the machine is provided with a forwardly extending table 274 which is secured to the forward portion of the bed 54. The forwardly extending table 274 is provided with vertically extending sides 276, 278 which form guides for a printed sheet 30. The bottom of the table 274 extends forwardly and under a bracket 280 having a portion spaced above the table and depending legs 282 which are fixed to the top of the table 54 as shown in Fig. 1. To insure that the leading edge of the sheet 30 is guided for movement under the bracket 280, guide member 284 is detachably secured to the table 54 by a knurled headed screw 286. Located just forwardly of the guide member 284, is a sheet positioning pointer 288 which is fixed, preferably frictionally, to the table 54 in any suitable manner so that its position can be adjusted, if need be, toward and away from the printing position for the purpose of properly registering the initial address on the work sheet. Said bracket member 280 has a lateral extension which is provided with rearwardly extending bosses which form bearings for a shaft 290 to which intermittently rotated feed wheels 292 are secured. The shaft 290 is provided at its end with a gear 293, Fig. 2, which meshes with a large gear 294 fixed to a stub shaft 296 mounted on a vertically extending bracket 298 secured to the top of the bracket member 280. At the other end of the stub shaft 296, is a ratchet wheel 300 having a pawl 302 mounted on a pawl carrying arm 304 rotatably mounted on the shaft 296. The pawl carrying arm 304 is pivotally connected to a link 306 which extends rearwardly and is provided at its rear end with a longitudinal slot and is adjustably secured at the upper end of a substantially vertical arm 308 rigidly connected to the top of the loop 72. By this construction, the feed wheel 292 is rotated step by step during each printing operation of the machine. A cooperating roller 310 is journaled on and between the top parts of a pair of upwardly extending arms 312 having an angularly related substantially horizontal portion 314 pivotally secured at 316 to a bracket 318 fixed to the bottom of the bed 54 of the machine. The arm 312 is normally urged upwardly by a spring 320 which bears against the lower end of the arm 312 and against an inclined bracket member 322 which may, as illustrated, be formed as a part of the bracket 318. The idler roll 310, therefore, is normally urged upwardly against the feed wheels 292 and into cooperating feeding relation therewith.

It is necessary properly to position the sheets for the first addressing printing operation and to this end, the indicating member or pointer 288 is provided and is so located forwardly of the printing mechanism that the blank portion 36 of the expiration notice 32 is located below the impression head 66 when the indicating member 288 is opposite to an indicating mark

324 on the sheet 30. This mark is preferably printed but any other suitable means may be provided if desired. The mark, for instance, may be a printed line on the sheet. It is apparent, therefore, in order to properly position the sheet 30 for the first printing operation, that the feed rolls 292 and 310 must be separated to permit the insertion of the leading end portion of the paper sheet. To this end, mechanism is provided for moving the idler or presser roll 310 downwardly away from the feed wheels 292. The machine is provided with a treadle 326 pivotally secured to the base of the machine at 328. The pedal 326 extends beyond the pivot point and has a downwardly extending boss 330 to which is pivotally secured a substantially vertical link 332, the upper end of which is pivotally secured to one arm of a bell crank lever 334. The bell crank lever 334 is pivotally secured to a depending bracket 336 which is fixed to the bottom of the bed 54 of the machine. The other arm of the bell crank lever 334 is pivotally connected to an upwardly extending link 338 which is pivotally connected to the downwardly extending arm 340 of the bell crank lever 342 which is pivotally secured to a downwardly extending portion of the bracket 318. The other arm of the bell crank lever 342 is provided with a cam portion 344 which engages a cam roll 346 fixed to the end of the laterally extending arm 314. Thus, when the treadle 326 is depressed the feed roll 310 will move in a counterclockwise direction away from the feed roll 292 a distance sufficient to permit the insertion of the forward end portion of the sheet 30.

The boss 330 is also pivotally connected to another link 348 which extends upwardly toward the rear of the machine and above the latch member 172 to control the operation of the continuously rotating sheet feeding mechanism, as will now be described. Referring now to Fig. 1, also Figs. 2, 5, and 10, it will be noted that the machine is provided with rearwardly extending members 350 and 352. The member 350 is in the form of a table which is inclined slightly downwardly away from the rear edge of the table 54. The member 350 is secured to the rear portion of the table 54 by brackets 354 and 356. The bracket member 354 extends upwardly and rearwardly away from the rear edge of the table and has substantially horizontally rearwardly extending portions 355, 357 which are secured to the under surface of the member 350. The table or member 350 is also connected adjacent to its forward end to a rearwardly extending supporting arm 361 by a bracket member 356a secured thereto and the rear end of the arm 361 is connected to the table 350 by a bracket 356b. The rearward portion of the table 350 is also supported by a brace 358 which is secured to a support 58 and extends upwardly and rearwardly to a member 359a to which it is rigidly secured. The member 359a is secured to the rear end portion of the member 350 by screws or other suitable means. The brackets 354, 356 are secured to substantially vertical members 359, 361 provided with bosses arranged to receive a shaft 368 to which a feed roll 370 is secured. The feed roll 370 is driven by a spring belt 372 from a shaft 374 which in turn is rotated through belt connections to the continuously operating jack shaft 116. The feed roll 370 is thus continuously rotated but is effective to feed the work only when a pair of cooperating idler wheels 376 are brought into cooperating feeding relation there-

with. These idler wheels 376 are rotatably mounted upon a shaft 378 mounted on a swinging bracket 380 which is pivoted at 382 to the rear end of the forwardly extending bracket member 383. The idler rolls 376 are thus free to move toward and away from the feed roll 370. As is shown most clearly in Figs. 2 and 5, the idler wheels 376 are normally held away from the feed roll 370 by a pin 384 mounted in one end of a lever 386 fixed to one end of a horizontal shaft 388. The shaft 388 is mounted in bearings 390 fixed to the bracket 84 and extending rearwardly thereof. The other end of the shaft 388 is provided with a rearwardly and downwardly extending arm 392 which in turn is pivotally secured to the upper end portion of the upwardly and rearwardly extending link 348. Thus when the pedal 326 to which the link 348 is pivotally secured is depressed, the arms 386 and 392 are moved in a clockwise direction moving the pin 384 away from the arm 392 thus permitting the arm and the wheels 376 to move toward and into engagement with the sheet of paper overlying the roll 370. Since the roll 370 is constantly rotating at a relatively high rate of speed, the sheet of paper will be fed forwardly from the position shown in Fig. 16 to the position shown in Fig. 18 during the time when the operator inserts another sheet between the cooperating feed rolls 292, 310.

The sheet above referred to is fed rearwardly step by step onto the rearwardly extending table 350 between address printing operations. The table 350 is provided with a positioning member 394 which may be adjustably fixed to the rear end of the table 350. The table 350 is also provided with a sheet pusher member 396 which extends longitudinally of the table 350 and is provided with an upstanding side portion 393. The guide member 396 is operated to move the sheet laterally. The table 350 is provided at about its middle longitudinal area with a slot 400 for receiving a longitudinally extending member 402 to which the member 396 is secured by screws 404. The longitudinal member 402 is slidably mounted on guide rods 406, 408. The guide rods 406, 408 extend through holes formed in the depending side portion 410 of the table 350. The end portions of the guide rods 406, 408 are fixed in supporting blocks 412, 414 which are fixed to the table 350 adjacent to the depending side portion 410 by screws 416, 418 respectively. The other ends of the rod 406, 408 are fixed in supporting blocks 420 and 422 which are secured to the bed of the table 350 by pairs of screws 424, 426.

The bracket member 462 is constantly urged toward the right, as viewed in Fig. 1, by springs 428, 430 secured to the ends of the member 462 and to the supporting blocks 420 and 422. The member 462 carries a depending cam roll 432 which by the aforesaid springs 428, 430 is held in engagement with a cam 434 rotatably mounted on a shouldered cap screw 436. The shouldered cap screw 436 is threaded into a bracket 438 secured to the table 350 by screws 440. A ratchet wheel 442 is secured to the cam member 434 by screws or other suitable fastenings for conjoint rotation therewith. It is to be noted that the ratchet wheel 442 is provided with six teeth which are equal to the number of printing operations to be performed on a single sheet.

The cam member 434 and the ratchet wheel 442 are rotated step by step by a cooperating pawl member 444 pivoted on a pawl arm 446 rotatably

mounted on the shouldered cap screw 436. The pawl 444 is normally held in engagement with the ratchet wheel 442 by a tension spring 448. The ratchet wheel 442 and the cam disc 434 associated therewith are prevented from overthrow by a spring brake composed of a plurality of springs 447 located in holes found in the bracket 438. The lower ends of the springs 447 bear against a metal washer 449 overlying a fibre washer 451. Said fibre washer bears against the upper surface of the cam disc 434 and effectively prevents overthrow of the disc and ratchet. The pawl 444, during its return movement, functionally engages the ratchet wheel 442 and may cause retrograde movements of the wheel and disc. A locking pawl 453 is provided which is pivotally mounted in a block 455 located between the supporting blocks 412. The locking pawl 453 is maintained in engagement with the ratchet wheel 442 by a tension spring 457. Said pawl arm 446 is pivotally secured to a substantially horizontally extending link 451 which is provided at its free end with a longitudinally extending slot 452 and a laterally extending slot 454. A pin 456 is secured to the extension of the arm 232 of the stencil-pusher bell crank 228 and is arranged to enter the slot 452 and the lateral extension 458 thereof. The link 451 is normally urged in a counter-clockwise direction as viewed in Fig. 8, by a spring 458 so that the pin 456 is located in the lateral extension 454 whereby to cause the link to oscillate. The pin 456 is arranged to be positioned in alignment with the longitudinally extending slot 452 for the purpose of preventing operation of the link 451, by a bell crank lever 460 pivotally mounted on a vertically extending stud 462 fixed to the lower end of the downwardly and rearwardly extending bracket member 410. One arm of the bell crank lever 460 is arranged to engage the link 450 to move it in a crosswise direction to bring the pin 456 into alignment with the longitudinally extending slot 452. This movement of the bell crank 460 is effected by the aforesaid printing controlling lever 160 which is arranged to engage the other arm of the bell crank lever 460 when said lever 160 is locked in position to disconnect the operating arm 92 and the operating sector 100 and thereby disable the printing mechanism. Thus, the ratchet 442 cannot be rotated except during the address printing operations of the machine.

It is to be noted that the cam member 434 has a cylindrical configuration for the angular space of approximately four teeth of the associated ratchet and has a depressed portion 434a between the fourth and the sixth tooth. Thus, as the cam is caused to rotate in a step by step manner, no movement of the sheet pusher member 396 takes place during the engagement of the cylindrical portion of the cam with the associated cam roller 432. At the end of the last cycle of the machine, however, the valley portion of the cam confronts the roller and hence during this stroke of the cam the sheet pusher member is caused to move laterally and to feed the overlying sheet into the action of the severing mechanism. This movement of the sheet pusher member takes place during the latter part of the first cycle of printing operations on a succeeding sheet, the sheet extracting rolls 370, 376 operating sufficiently fast to extract the sheet from its position between the elements of the printing mechanism and to deposit the sheet upon the sheet receiving table 350 while the cam is stationary due to the inaction of the printing mechanism.

The severing mechanism 464, as most clearly shown in Fig. 10, comprises a plurality of co-operating rotating knives 466, 468 three sets being here shown. The knives 466 are mounted on a shaft 470 which extends longitudinally and substantially horizontally at the right of the table 350. The shaft is journalled in downwardly extending end portions of a bracket carrying member 472 fixed at one end to the bed of the machine through the bracket 473 and at the rear end to an upwardly extending angular bracket 474 having an upwardly extending portion and a substantially horizontal portion connected to the member 357, the latter portion being also secured to the brace 358. As aforesaid, there are three knives 466 secured to the shaft 470 and these knives are each secured to a supporting member or hub 476 which is fixed to the shaft 470. The cooperating knives 468 are mounted on a shaft 478 which extends below and parallel to the shaft 470. This shaft 478 is journalled at one end in the upwardly extending portion of the bracket 474 and at its other end to the upwardly extending portion of the bracket member 356. The cooperating circular rotating knife members 468 are secured to hub portions 480 and are substantially identical to the knives 466 and the hubs 476. The shaft 478 is provided at the end adjacent to the bed 54 of the machine with a pulley 482 which is belt driven from a pulley 484 fixed to a horizontal shaft 486 and journalled in bearings formed in a bracket 488 secured to the top of the bracket 84. The other end of the shaft 486 is provided with a pulley 490 which is belt driven from a pulley mounted on a shaft 374 hereinbefore referred to. The shaft 470 is driven from the shaft 478 by spur gears 492, 494 fixed to the respective shafts 470, 478. The knives 466 and 468 are thus constantly rotated during operation of the machine. The shafts 470 and 478 are provided with cooperating feed wheels 496, 498 there being two sets of these cooperating wheels for each set of knives to insure that the severed forms will be fed in straight lines onto a traveling belt 500 mounted on the member 352 which moves the severed forms into a container 502 mounted at the rear end portion of the member 352.

As illustrated, the endless delivering belt 500 is mounted on pulleys 504 and 506 secured to shafts journalled at one end in rearwardly extending side supporting members 361 and 368, the member 508 being secured at its rearward end to the upwardly extending arm 474 of the bracket member 359 and at its forward end to a bracket member 475 secured to the table 54. The travelling belt 500 is held tight by a tensioning roller 514 carried by and rotatable between the free ends of arms 516 which are pivotally secured by a shaft 518 to the side members 361, 368. The arms 516 are urged in a belt tightening direction by springs not necessary to illustrate. The forward pulley 504 is belt driven from a pulley 520 fixed to the shaft 374 hereinbefore referred to, so that the belt 500 is constantly travelling in a direction away from the table 54. Below the forward end of the travelling belt 500 is a container 524 which is fixed to one of the supports 56 of the machine. This container 524 is arranged to receive the waste end of the severed sheet.

It is to be noted at this point that the pair of knives 466, 468 located next to the bed 54 of the machine are located in a position which is just forward of the forward end of the belt 500. Thus when the feed tab end of a sheet is severed

it will slide forwardly of the belt and will drop into a downwardly extending chute 526 and into the waste receiver 524.

Although the construction and operation of the 5 illustrated machine has been described in detail, it is believed advisable, for a clearer understanding of the present invention to summarize briefly the operation of the machine. The operative depresses the treadle 326 to separate the step-by-step sheet feeding members 292, 310 inserts the leading edge portion of a sheet between the feeding members and locates the mark 324 on the sheet opposite to the pointer 288. The operative then releases the treadle 326 and depresses the 10 treadle 120 to start the machine. If a wanted stencil is in printing position, the printing mechanism will make two successive impressions on the sheet from that one stencil, the sheet being advanced between successive printing operations. 15 After the completion of the second printing operation, the stencil is moved out of printing position and another wanted stencil is fed into printing position. Two impressions are made on the sheet from this stencil and the sheet is fed forwardly step by step between successive printing operations. The same operations are performed 20 on the sheet with a third stencil and the addressed sheet now has its leading edge portion projected between the feeding members 370, 376 in the position shown in Fig. 16. After the completion of the last printing operation, the operative releases the treadle 120 and depresses the treadle 326 preparatory to inserting a second sheet in the machine. As the treadle 326 is depressed the feed roll 370 and presser wheels 376 are brought into cooperating feeding relation with the paper sheet therebetween. The roll 370 is constantly rotated at a relatively high rate of speed and moves the sheet rapidly into the table 350 in position to be moved laterally to the action of the severing means. During this time, the operative has inserted a second sheet in the machine in proper position, released the treadle 326 and depressed the treadle 120 to start printing operations on the second sheet, the lateral sheet feeding means 396 and the sheet now located thereon is moved toward the right as viewed in Fig. 1 to the action of the severing means 466, 468. The sheet is engaged by the feed rolls between the pairs of severing devices.

50 The severed pairs of receipts and notices drop upon the belt 500 and are conveyed to the receiver. During the address printing operation, the lateral sheet feeder 396 is returned to its original position as shown in Fig. 18. The machine continues to operate and the operations are repeated until the required number of addresses is printed.

55 Although the invention has been described herein with particular reference to one illustrated embodiment thereof, it is to be understood that the invention is not limited thereto but that changes can be made within the scope of the appended claims.

Having thus described my invention, what I claim as new and desire to secure by Letters Patent of the United States is:

60 1. In an addressing machine, address printing mechanism, means for feeding a sheet through said printing mechanism in a step by step manner to permit a plurality of printing operations to be performed thereon, means for feeding successive address printing devices to the action of said printing mechanism at intervals between plural printing operations thereof, means for feeding said sheet laterally after the last printing operation has been completed, and means for

severing the sheet during the operation of the last mentioned feeding means.

2. In an address printing machine, address printing mechanism, means for feeding sheets to said printing mechanism to permit printing operations to be performed thereon, means for severing said sheet, and means for feeding the sheet laterally after the printing has been completed to move said sheet into engagement with the severing means.

3. In an addressing machine, address printing mechanism, means for feeding sheets to said printing mechanism to permit printing operations to be performed thereon, means located at one side of the path of feed of said feeding means for severing said sheets, and means for feeding said sheets laterally to said severing mechanism after printing operations have been performed on said sheets.

4. In an addressing machine, address printing mechanism, means for feeding sheets step by step to said printing mechanism to permit a plurality of printing operations to be performed on said sheets, means located at one side of the path of feed of said step by step feeding means for severing said sheet into a plurality of parts, and feeding means operative to feed said sheets laterally to said severing mechanism after printing operations thereon have been completed.

5. In an addressing machine, address printing mechanism, means for feeding sheets to said printing mechanism to permit printing operations to be performed thereon, rotating knives for severing said sheet, and means for feeding the sheet laterally into engagement with said rotating knives after the printing operations have been completed.

6. In an addressing machine, address printing mechanism, means for feeding sheets step by step to said printing mechanism to permit printing operations to be performed thereon, continuously operated means located at one side of the path of feed of the step by step feeding means for severing the sheets into a plurality of parts, and feeding means operative to feed the sheets laterally to said continuously operated severing means after printing operations have been performed thereon.

7. In an addressing machine, address printing mechanism, means for feeding sheets to said printing mechanism to permit printing operations to be performed thereon, means arranged to engage the sheet after the last printing operation has been completed thereon for continuing the feed of the sheets in the same direction as the first mentioned feeding means, means for severing said sheet, and means for feeding the sheet laterally after the completion of the operation of said second feeding means to move the sheet into engagement with the severing means.

8. In an addressing machine, address printing mechanism, means for feeding sheets to said printing mechanism to permit a plurality of printing operations to be performed thereon, means for severing said sheets, means inoperative during the step by step movement of said first mentioned feeding means and operative after the last printing operation has been performed upon the sheet to continue the feed of the sheet in the same direction as the feeding movement of the first mentioned feeding means, and means for feeding the sheet laterally after the completion of the feeding movement of said second mentioned feeding means for moving the sheet into engagement with said severing means.

9. In an addressing machine, address printing mechanism, means for feeding sheets step by step to said printing mechanism to permit printing operations to be performed thereon, means located at one side of the path of feed of said step by step feeding means for severing said sheets into a plurality of parts, means inoperative during the step by step feeding movement of the first mentioned feeding means and operative after the last printing operation has been completed to continue the feed of the sheets in the same direction, and feeding means operative to feed the sheets laterally to the severing means after the second feeding means has completed its feeding movement.

10. In an addressing machine, address printing mechanism, means for feeding sheets to said printing mechanism to permit a plurality of printing operations to be performed thereon, rotating knives for severing said sheets, means for feeding the sheets in the same direction after the printing operations have been completed, and means for progressively and continuously feeding the sheets laterally after the second feeding means has completed its operation to move the sheets into engagement with said rotating knives for severing said sheets.

11. In an addressing machine, address printing mechanism, means for feeding sheets to said printing mechanism to permit a plurality of address printing operations to be performed thereon, means for severing said sheet, means for feeding the sheet laterally after the printing operations have been completed on the sheet to move the sheet into engagement with the severing means, means for receiving the severed parts, and means for feeding the severed parts to said receiving means.

12. In an addressing machine, address printing mechanism, means for feeding sheets to said printing mechanism to permit printing operations to be performed thereon, rotating knives for severing said sheets into a plurality of parts, means for feeding the sheet laterally after the printing operation has been completed to move the sheet into engagement with said severing means, a receiver for the severed sheets, and means for feeding the severed parts of the sheets to said receiver.

13. In an address printing machine, address printing mechanism, means for feeding sheets to the printing mechanism to permit printing operations to be performed thereon, means for severing said sheet, means for continuing the feed of the sheet at the completion of the last printing operation thereon, means for feeding the sheet laterally after the completion of the operation of the second feeding means to move the sheet into engagement with the severing means, a receiver for the severed sheets, and means for feeding the severed sheets to the receiver.

14. In an addressing machine, address printing mechanism, means for feeding sheets to feed printing mechanism to permit a plurality of printing operations to be performed thereon, rotating knives for severing said sheets into a plurality of parts, means for continuing the feed of the sheets after the completion of the last printing operation in the same direction as the feeding movement of the first mentioned feeding means, and means for feeding the sheets laterally after the completion of the operation of the second mentioned feeding means to move the sheet into engagement with said rotating knives.

15. In an addressing machine, means for per-

forming a plurality of address printing operations on a sheet, means for feeding the sheet step by step between addressing operations, a plurality of knives mounted for rotation upon axes substantially parallel to the path of feeding movement of said step by step feeding means, and means for feeding the sheet transversely to said severing means after the completion of the addressing operations.

16. In an address printing machine, address printing mechanism, means for feeding a sheet past said address printing mechanism step by step to permit a plurality of printing operations to be performed thereon, means for severing the sheet transversely, a laterally movable member for feeding the sheet into engagement with said severing means and means for moving said laterally movable member toward said severing means and returning said member to its original position while printing operations are being performed on another sheet.

17. In an addressing machine, address printing mechanism, means for feeding a sheet past said address printing mechanism step by step to permit a plurality of address printing operations to be performed thereon, means for severing the sheet transversely into a plurality of parts, means for moving the sheet laterally into engagement with said severing means, and means for reciprocating said laterally movable feeding means while address printing operations are being performed on another sheet.

18. In an addressing machine, address printing mechanism, means for feeding a sheet past said address printing mechanism step by step to permit a plurality of address printing operations to be performed thereon, means for severing the sheet transversely into a plurality of parts, means for continuing the feed of the sheet in the same direction after the completion of the last address printing operation on the sheet, means for moving the sheet laterally into engagement with said severing means, and means for reciprocating said lateral movable feeding means while address printing operations are being performed on another sheet.

19. In an address printing machine, address printing mechanism, means for feeding a sheet past said address printing mechanism step by step to permit a plurality of address printing operations to be performed on the sheet, means for severing the sheet transversely into a plurality of parts, a laterally movable feeding member, means for feeding the sheet into said laterally movable feeding member after the last address printing operation has been performed on the sheet, and means for reciprocating said laterally movable feeding member after the second mentioned feeding means has completed its operation and before the last address printing operation is completed on another sheet.

20. In an addressing machine, printing mechanism, means for advancing printing devices in successive order to said printing mechanism, means for operating said printing mechanism to make a printing operation on an associated printing device, means controlling the operation of said device advancing means to maintain a wanted printing device in said printing mechanism for a predetermined period of time and an unwanted printing device for a lesser period of time, sheet feeding means for advancing a sheet through said printing mechanism in an intermittent manner in response only to the presence of wanted printing devices therein, means con-

trolled by said printing devices for effecting duplicate printing operations on the same wanted printing device on successive parts of the sheet and printing operations from different wanted

5 printing devices on different parts of the sheet, a sheet receiving device arranged to receive the addressed sheet, slitting mechanism arranged to advance the sheet laterally of its length and to sever the sheet into sections containing different addresses, means for advancing the addressed sheet laterally of its length into said slitting mechanism, and means for stacking the severed sections.

10 21. In an addressing machine, means for applying repetitions of the same address to successive portions of a sheet and different addresses to different successive portions of the sheet, a sheet receiver adapted to receive the addressed sheet, sheet severing mechanism disposed beside said receiver adapted to sever the sheet into sections between the portions bearing different addresses, and means associated with said receiver operative to advance the sheet laterally into the action of said severing mechanism.

25 22. In an addressing machine, means for applying different addresses to successive parts of a long sheet, a sheet receiver adapted to support the addressed sheet, a pusher member disposed beside the sheet on said receiver adapted to advance it laterally, pusher operating means including a cam having an operative engagement with said pusher member, means for advancing said cam in a step by step manner, said cam having a cam face engageable with a part of said pusher member so arranged that a part of the movement of said cam is free from corresponding movement of said pusher member, said cam having another part of its cam face so arranged as to effect a relatively rapid movement of said pusher member, and sheet slitting means arranged to receive the sheet advanced by said pusher member and sever it into sections containing different addresses.

30 23. In an addressing machine, means for applying different addresses to successive parts of a long sheet, a sheet receiver adapted to support the addressed sheet, a pusher member disposed beside the sheet on said receiver adapted to advance it laterally, pusher operating means including a cam having an operative engagement with said pusher member, means for advancing said cam in a step by step manner, said cam having a cam face engageable with a part of said pusher member so arranged that a part of the movement of said cam is free from corresponding movement of said pusher member, said cam having another part of its cam face so arranged as to effect a relatively rapid movement of said pusher member, and sheet slitting means arranged to receive the sheet advanced by said pusher member and sever it into sections containing different addresses, said severing mechanism also including means for advancing the sheet independently of said pusher, and means for stacking the severed sheet sections.

35 24. In an addressing machine, printing mechanism, means to advance a succession of printing devices to the action of said printing mechanism, means for advancing to the action of said printing mechanism and said successive printing devices a strip having a succession of address receiving sections and an address free end section, means for operating said printing mechanism to apply addresses to said address receiving sections of said strip, severing mecha-

nism operative to receive the addressed strip and to sever it into address containing sections and an address free section, and a conveyor belt arranged to receive the severed sections, said severing means being arranged relatively to said belt to deposit the address bearing sections of the strip upon a pass of said belt and the address free section of the strip at one end of the pass whereby said address free section can fall away from the belt.

25. In an address printing machine, address printing mechanism, a first pair of feed rolls on one side of the address printing mechanism for feeding sheets thereto, means for stepwise indexing of one of the first feed rolls between printing operations, a second pair of feed rolls on the opposite side of the address printing mechanism for feeding printed sheets therefrom, and means for separating the first feed rolls when the final printing operation has been effected on a sheet and simultaneously moving the second feed rolls relatively together, and for separating the second feed rolls when the first feed rolls are in sheet feeding relation.

26. In an address printing machine, address printing mechanism, a first pair of feed rolls on

one side of the address printing mechanism for feeding sheets thereto, means for stepwise indexing of one of the first feed rolls between printing operations, a second pair of feed rolls on the opposite side of the address printing mechanism for feeding printed sheets therefrom, means for advancing a succession of address-bearing printing devices to the action of the address printing mechanism, means for maintaining in printing position each said address-bearing printing device which is acted upon by the address printing mechanism until a plurality of printings are made therefrom, means for operating said first feed rolls for step by step advance of each sheet to the printing position until a plurality of impressions from each of a plurality of said address-bearing printing devices has been made thereon, and means for simultaneously moving the second feed rolls relatively together and the first feed rolls relatively apart when the final printing operation has been effected on a sheet, and for separating the second feed rolls when the first feed rolls are in sheet feeding relation.
